ELOF H. MEDEN, OF SHORT HILLS, NEW JERSEY, ASSIGNOR TO AMERICAN GAS-ACCUMULATOR COMPANY, OF ELIZABETH, NEW JERSEY, A CORPORATION OF NEW JERSEY.

DESIGN FOR A WELDING-BLOWPIPE OR SIMILAR ARTICLE.

59,368.

Specification for Design.

Patented Oct. 11, 1921.

Application filed March 18, 1920. Serial No. 366,993. Term of patent 14 years.

To all whom it may concern:

Be it known that I, ELOF H. MEDEN, a subject of the King of Sweden, residing in the city of Short Hills, county of Essex, State of New Jersey, have invented a new, original, and ornamental Design for a Welding-Blowpipe or Similar Article, of which the following is a specification, reference being had to the accompanying drawing, forming a part hereof, and in which—

Figure 1 is a view in side elevation of a welding blow pipe embodying my design; and

Fig. 2 is a top plan view of the same. The shade lines 6 shown in Fig. 1 of the drawing are not intended to indicate particular colors but merely that the colors of the said figures are different or in contrast.

I claim:

The ornamental design for a welding blow pipe or similar article, as shown.

In testimony whereof I have hereunto signed my name this 11 day of March, A. D. 1920.

ELOF H. MEDEN.
